DOOR CONSTRUCTION

Hans Hanson, Portland, Oreg.

Application July 28, 1938, Serial No. 221,825

1 Claim. (Cl. 20—35)

This invention relates to new and useful improvements in door constructions.

The principal object of the present invention is to provide a door construction of sturdy yet 5 inexpensive construction.

Another important object of the invention is to provide a door of veneering construction wherein unusual sturdy bracing and internal construction is employed.

10 Other important objects and advantages of the invention will become apparent to the reader of the following specification.

In the drawing:

Figure 1 represents a side elevational view of 15 the door shown braced but without the veneering.

Figure 2 is a vertical sectional view of the door showing the bracing but without veneering.

Figure 3 is a perspective view of the one of 20 the connecting members.

Figure 4 is a perspective view of one of the corner members.

Referring to the drawing wherein like numerals designate like parts, it can be seen that 25 numeral 5 denotes the frame of the door which consists of the top and bottom members 6 and 7 and the side members 8 and 9.

Numerical 10 represents a cross member which 30 connects the intermediate portions of the side portions 8 and 9 of the door frame and the ends of this cross member 10 are dovetailed as at 11 into the side members 8 and 9.

Thus upper and lower door frame openings 35 are defined in which brace means are installed in carrying out the present invention.

In carrying out the present invention, in each of the last-mentioned door spaces is disposed an octagon-shaped frame 11 and across each corner of these openings, including the corners defined 40 by the cross member 10 is disposed a corner member 12, the end portions of which are inset as at 13 into the end and side members and

cross member 10 of the door as clearly shown in Figure 1.

To complete the connecting and reinforcing of this structure, the connecting or brace members 14 are disposed in a manner connecting either the door frame or the corner members 12 or the cross member 10 with the corresponding octagon frame 11. The end portions of the brace members 14 each has its inner end dovetailed as at 15 into a corresponding side 10 portion of the frame 11 and its outer end portion dovetailed either to the dovetailed opening 16 of a corner member 12 or into the door frame as at 17 or into the cross member 10 as at 18.

These members 12 and 14 as well as the frame 15 11 and cross member 10 are of a thickness equal to the thickness of the door frame so that their outside surfaces will be flush with the outside surfaces of the door frame 5.

Obviously in finishing the door construction, 20 veneering is applied to opposite sides of the door frame and aforementioned reinforcing means so as to completely conceal the same.

While the foregoing specification sets forth the invention in specific terms, it is to be understood 25 that numerous changes in the shape, size and materials may be resorted to without departing from the spirit and scope of the invention as claimed hereinafter.

Having described the invention, what is 30 claimed as new is:

In a door structure, a frame, a cross member dividing the frame into a pair of open areas, a centrally located structure in each of the areas and brace members extending from the centrally 35 located structure to the frame and cross member, and having their ends dovetailed into the frame and cross member, and corner members into which certain of the brace members have their outer ends dovetailed.

40 HANS HANSON.
